Primary Examiner — Messina L Smith

(57) **CLAIM**

The ornamental design for a toaster, as shown and described.

DESCRIPTION

The patent or application file contains at least one drawing executed in color. Copies of this patent or patent application publication with color drawing(s) will be provided by the Office upon request and payment of the necessary fee.

1. Toaster

1.1: Front

1.2: Back

1.3: Left

1.4: Right

1.5: Top

1.6: Bottom

1.7: Perspective

The portions of the design shown in the color red are for the purpose of illustrating portions of the toaster and form no part of the claimed design.

1 Claim, 7 Drawing Sheets
(3 of 7 Drawing Sheet(s) Filed in Color)
